To all whom it may concern:

Be it known that I, Samuel Zahn, a citizen of the United States of America, residing in Manhattan, county of New York, and State of New York, have invented a new, original, and ornamental Design for a Dress, of which the following is a specification, reference being had to the accompanying drawing, forming part thereof, wherein,

The horizontal lines on the front and back of shoulders represent tucks.

The horizontal lines in the belt and the vertical parallel lines extending from the front of the blouse and around the neckline represent pipings of self material.

The cross hatched panel at the outer edge of the sleeve represents an opening.

I claim:

The ornamental design for a dress, substantially as shown and described.

SAMUEL ZAHN.
